CHILDREN'S GLIDE SWING

John A. Conti, Dothan, Ala.

Filed Feb. 4, 1964, Ser. No. 78,509

Term of patent 7 years

(Cl. D34—5)

FIG. 1 is a perspective view of a children's glide swing embodying my new design;

FIG. 2 is a fragmentary enlarged perspective view from the front thereof; and

FIG. 3 is a fragmentary enlarged perspective view from the rear thereof.

The dominant features of my design reside in the portions shown in full lines.

The fragmentary broken line disclosure of a swing support shown in FIG. 1 is for illustrative purposes only.

I claim:

The ornamental design for a children's glide swing, substantially as shown and described.
